UNITED STATES PATENT OFFICE.

VERNON H. BROWN, OF NEW YORK, N. Y.

LOADING DEVICE.

1,385,110.

Specification of Letters Patent. Patented July 19, 1921.

Application filed November 30, 1920. Serial No. 427,448.

To all whom it may concern:

Be it known that I, VERNON H. BROWN, a citizen of the United States, residing at New York, in the county of New York and 5 State of New York, have invented new and useful Improvements in Loading Devices, of which the following is a specification.

This invention relates to a device intended, primarily, though not exclusively, 10 for loading trucks, such as are used for the collection of ashes, garbage, and the like.

The device is intended, particularly, for use in connection with a vehicle having a movable receiving chamber or bed, whereby 15 the material may be dumped therefrom. An object of the invention is the provision of a loading device which may be secured to the vehicle chassis and be movable toward and away from the receiving bed so that when 20 the material is to be dumped from the bed the loading device may be swung away therefrom, and the bed moved without removing the conveyer frame from the vehicle.

Another feature of the invention resides 25 in the provision of a chute which is adjustable, preferably, in both vertical and horizontal planes, and which receives the material from the conveyer and distributes the same over the receiving bed.

30 Other features and objects of the invention, such as the provision of releasable means for holding the conveyer frame adjacent the vehicle bed, means for limiting the movement of the conveyer frame away from 35 the bed, and the construction of the conveyer, will become obvious from a reading of the following description and an inspection of the accompanying drawings, wherein there is disclosed and described one form of 40 a device in which the invention may be embodied.

In the drawings:

Figure 1 is a side elevational view of a portion of a truck showing the loading device applied thereto.

45 Fig. 2 is a horizontal cross sectional view on the line 2-2 of Fig. 1.

Fig. 3 is a plan view of the operating mechanism for the conveyer.

50 Fig. 4 is a cross sectional view of the chute device on the line 4-4 of Fig. 2.

Fig. 5 is a bottom plan view of the stationary funnel member, and

Fig. 6 is a vertical sectional view through

the chute supporting track showing the 55 clamp for the chute.

Referring to the drawings for a more detailed description, 10 indicates, generally, a vehicle which may be of any type, having, in the present instance, supported upon its 60 chassis 11 a receiving chamber 12, which is movably mounted upon the chassis so that the material may be dumped therefrom. The receiving chamber is shown as pivoted to the chassis at 13 and the vehicle is provided with hoisting mechanism 14, whereby the receiving bed may be swung upwardly about its pivot.

Positioned adjacent the receiving bed, and in the drawings shown as at the side of the 70 same, is a conveyer frame 15 which comprises the vertically extending side strips 16, 17 connected by cross pieces 18, and further strengthened by diagonally extending braces 19 running between the cross strips 18. The 75 vertically extending side strips 17 are pivotally connected at their lower ends 20 to horizontally extending frame portions 21 running beneath the receiving bed and secured at 22 to the chassis of the vehicle. 80 Upon the conveyer frame may be mounted any suitable form of conveyer mechanism which, in the illustrated embodiment of the invention, comprises a pair of traveling chains 23, 24, having secured thereto a material receiving bucket 25. The conveyer chains traverse the lower sprockets 26 fixedly secured upon a shaft 27, which has bearings in brackets 28 depending from the horizontal frame members 21 and extend 85 upwardly to top sprockets 29 mounted upon a shaft 30 in the upper end of the side strips 16 and 17. Idlers 31 may be positioned above the lower sprockets 26 and idlers 32 below the top sprockets 29 in order to guide 90 the downward run of the chain.

In Figs. 1 and 2 the conveyer is shown as positioned in a vertical plane at the side of the receiving bed, and releasable means should be provided for maintaining the conveyer in this position. In the drawings U-shaped latches 34 are positioned in the central frame cross strip 18 so as to fit over the top edge of the receiving chamber side wall and accomplish this purpose. Obviously, 100 when it is desired to permit the conveyer frame to swing away from the receiving bed 105 so that the latter may be moved to dump the

- material, the latches are rotated in their bearings in the cross strip 18 and the conveyer frame will swing about its pivots 20 to the dotted line position shown in Fig. 2.
- 5 In order that the outward swinging movement of the conveyer frame may be limited, an arm 36 may be secured to the side strip 16 (Fig. 2) and have at its end a pin 37 extending into a slot 38 in the frame strip 21.
- 10 Obviously, when the conveyer frame swings away from the receiving bed its outward movement will cease when the pin 37 reaches the end of its guide slot.
- The invention is also characterized by the provision of means for distributing the material about the receiving bed, and in the drawings there is shown secured to the upper end of the conveyer frame a funnel 39 connected to the side strips 16 and 17 by means of brackets 40. Beneath the funnel, which, it will be observed, is positioned above the receiving bed when the conveyer frame is in vertical position, is positioned a chute 41 which is in the form of a pan-like member.
- 15 This chute is pivotally secured, at each side, to upwardly extending arms 42 by means of threaded pins 43 extending through the bracket, clamping nuts 44 being secured to the outer ends of the pins to secure the pan in any selected pivotal adjustment. The upper ends of the arms 42 are laterally and downwardly bent, as at 45, and have mounted therein rollers 46 which ride upon an annular track 47 positioned around the funnel 39 and supported by bracket arms 48 extending outwardly from the wall of the funnel. It will be obvious that the chute supporting arms 42, by riding upon the track 47, permit an adjustment of the chute 41 in a horizontal plane, and to secure the arms in any selected horizontal adjustment, a pair of parallel clamping bars 49, 50 may be secured to one of the arms 42 at their lower ends 51 and extend rearwardly and upwardly to each side of the track 47 (Figs. 2 and 6), which may, at any time, be clamped between the clamping bars 49, 50 by means of a bolt 52 passing through the clamping bars and having an adjusting nut 53.
- 20 The conveyer mechanism may be operated either manually or by mechanically operated means operable from the motor of the vehicle. Referring to Fig. 3, there is shown a driving mechanism which is intended to be operated from the vehicle motor.
- 25 55 indicates a shaft such as the counter shaft of the vehicle, having bearings in brackets 56 depending from the chassis. Paralleling this shaft are two counter shafts 57 and 58 supported in brackets 59, also depending from the chassis. The shaft 57 has fixedly secured thereto a spur gear 60 meshing with a spur gear 61 fixedly secured upon the counter shaft 55, and has, also, a pulley 62 traversed by a drive belt 63 passing
- around a pulley 64 revolvably mounted upon shaft 58. Upon the rear end of shaft 55 is fixedly secured a pulley 65 which, through belt 66, is adapted to rotate pulley 67 revolvably mounted upon shaft 58. Upon the rear end of shaft 58 is fixedly secured a pulley 68 which, through belt 69, drives a pulley 70 fixedly secured upon the lower sprocket shaft 27, and drives the conveyer chains. From the above description it will be apparent that rotation of shaft 55 from the motor will drive the two loose pulleys 64 and 67 upon shaft 58 in opposite directions. Either of these pulleys may be connected to the shaft 58 for driving the same by means of a clutch 71 slidably keyed to the shaft 58, and operable by means of a shifting arm 72 having a forked end 73 engaging the clutch and pivotally connected to an operating lever 74. The operating lever may be used to maintain the clutch in neutral position so that the conveyer is not operated, or may be moved to the right or left, as shown in Figs. 1 and 3, to cause either upward or downward movement of the conveyer mechanism.
- 30 In operating the device in order to load the vehicle, the conveyer frame is maintained in the position in which it is shown in Figs. 1 and 2 by means of the latches 34. The receptacle 25, which will ordinarily be of sufficient size to receive the contents of an ash can or the like, will be normally in its lowered position shown in the views. When the material to be deposited into the receiving chamber is placed in the bucket 25 the shifting lever 74 will be operated to throw the clutch into engagement with the pulley 64, whereupon the bucket will be carried upwardly to the dotted line position shown in Fig. 2 and its contents emptied through the funnel 39 upon the chute 41, which will direct the material to the bed of the receiving chamber. After the contents of the bucket has been emptied the clutch will be operated to reverse the drive and the bucket will be lowered to the full line position shown in Fig. 2. As different parts of the bed of the receiving chamber become filled the chute 41 will be adjusted about its pivots 43 in a vertical plane, and will also be adjusted in a horizontal plane by rotating the arms 42 about the track 47, these adjustments being made when desired. When the receiving chamber has been filled and it is desired to dump the material therefrom the latches 34 will be lifted and the conveyer frame swung outwardly to the dotted line position shown in Fig. 2. The hoisting mechanism 14 may then be operated to swing the receiving chamber 12 upwardly about its pivot 13, and after the material has been dumped the receiving chamber will be returned to its normal position and the conveyer swung inwardly to the full line position shown in Figs. 1 and 2.

- It will, of course, be understood that while I have shown and described a specific mechanism in detail, the invention is not limited to the structural details shown, for the specific mechanism shown in the drawings might be materially modified without departing from the scope of the invention, which is more definitely defined in the following claims.
- 10 Having fully described my invention, what I claim is:
1. The combination with a vehicle having a material receiving bed, of a conveyer frame secured to the vehicle chassis and adapted to be moved toward and away from the receiving bed, a conveyer on said frame, means for operating said conveyer, and releasable means for holding said conveyer and its frame in position adjacent the receiving bed whereby the conveyer may deposit material thereupon. 15
  2. The combination with a vehicle having a movable material receiving bed, of a conveyer frame secured to the vehicle chassis and adapted to be moved pivotally toward and away from the receiving bed, a conveyer on said frame, means for operating said conveyer, and releasable means for holding said conveyer and its frame in position adjacent the receiving bed whereby the conveyer may deposit material thereupon. 20
  3. The combination with a vehicle having a movable material receiving bed, of a conveyer frame secured to the vehicle chassis and adapted to be moved pivotally toward and away from the receiving bed, a conveyer on said frame, means for operating said conveyer, means for limiting the movement of said frame away from the receiving bed, and releasable means for holding said conveyer and its frame in position adjacent the receiving bed whereby the conveyer may deposit material thereupon. 25
  4. The combination with a vehicle having a material receiving bed, of a conveyer frame secured to the vehicle chassis and adapted to be moved toward and away from the receiving bed, a conveyer on said frame, means for operating said conveyer, a chute positioned above the receiving bed to receive material from said conveyer and adjustable in a vertical plane whereby the material may be distributed about said receiving bed, and releasable means for holding said conveyer and its frame in position adjacent the receiving bed whereby the conveyer may deposit material thereupon. 30
  5. The combination with a vehicle having a movable material receiving bed, of a conveyer frame secured to the vehicle chassis and adapted to be moved toward and away from the receiving bed, a conveyer on said frame, means for operating said conveyer, a chute positioned above the receiving bed to receive material from said conveyer and ad- 35
  - justable in both vertical and horizontal planes whereby the material may be distributed about said receiving bed, and releasable means for holding said conveyer and its frame in position adjacent the receiving bed whereby the conveyer may deposit material thereupon. 40
  6. The combination with a vehicle having a movable material receiving bed, of a conveyer frame secured to the vehicle chassis and adapted to be moved toward and away from the receiving bed, a conveyer on said frame, means for operating said conveyer, a vertically and horizontally adjustable chute secured to said frame and adapted to be positioned over the receiving bed when the conveyer frame is in position thereagainst, and releasable means for holding said conveyer and its frame in position adjacent the receiving bed whereby the conveyer may deposit material thereupon. 45
  7. The combination with a vehicle having a material receiving bed movable to permit the dumping of material therefrom, of a conveyer frame secured to the vehicle chassis and adapted to be moved toward and away from the receiving bed, a traveling chain and bucket conveyer on said frame, means for operating said conveyer, a vertically and horizontally adjustable chute on said frame adapted to be positioned above the receiving bed when the frame is in position adjacent the bed, means for limiting the movement of said frame away from the receiving bed, and releasable means for holding said frame in position adjacent the bed. 50
  8. A vehicle loading device comprising a conveyer frame adapted to be positioned in a vertical plane adjacent a vehicle, means for securing the frame to a vehicle chassis so that it is movable toward and away from the vehicle body, means for holding the conveyer frame in substantially vertical position at the side of a vehicle body, means for limiting the movement of the frame away from the body, and means for operating the conveyer. 55
  9. A device as specified in claim 8, said conveyer frame having a vertically and horizontally adjustable chute secured thereto so as to be positioned above the receiving bed of a vehicle when the conveyer frame is in substantially vertical position. 60
  10. A device as specified in claim 8, said conveyer frame having a vertically and horizontally adjustable chute secured thereto so as to be positioned above the receiving bed of a vehicle when the conveyer frame is in substantially vertical position, and a funnel located above said chute to direct the material thereto. 65
  11. The combination with a vehicle having a movable material receiving bed, of a conveyer frame secured to the vehicle chassis and adapted to be moved toward and away from the receiving bed, a conveyer on said frame, means for operating said conveyer, a chute positioned above the receiving bed to receive material from said conveyer and ad- 70
